UNITED STATES PATENT OFFICE.

ALFRED H. CRAMPTON, OF STOCKTON, CALIFORNIA.

DESIGN FOR A COMBINATION HAMMER, CAN-PUNCH, AND ICE-PICK.

55,592.

Specification for Design.

Patented July 6, 1920.

Application filed February 4, 1920. Serial No. 356,244. Term of patent 14 years.

To all whom it may concern:

Be it known that I, ALFRED H. CRAMPTON, a citizen of the United States, residing at Stockton, in the county of San Joaquin and State of California, have invented a new, original, and ornamental Design for a Combination Hammer, Can-Punch, and Ice-Pick, of which the following is a specification, reference being had to the accompanying drawing, forming part thereof, in which—

Figure 1 is a side elevation of the appliance and Fig. 2 is an end view of the same.

The device is designed to be used as a hammer, a can puncher, and an ice pick.

I claim:

The ornamental design for a combination hammer, can punch, and ice pick, as shown.

ALFRED H. CRAMPTON.
